RELAY ADJUSTING FIXTURE

Alexander M. MacPheat, Indianapolis, Ind., assignor to Western Electric Company, Incorporated, New York, N. Y., a corporation of New York

Application July 7, 1950; Serial No. 172,503

7 Claims. (Cl. 153—10)

1

This invention relates to adjusting fixtures and more particularly to a fixture for adjusting parts of relays.

The fixture of the present invention is particularly adapted to the adjusting of parts of relays for use in telephone coin collector mechanism which may include a pivotal lever having a slotted lower end and various stop arms and lugs extending from the lever, pivotal spring actuated restoring levers for the lever and an associated armature carried upon a saddle member pivoted intermediate its ends on a frame which is fixed relative to a pair of coils having their cores fixed to a base plate. The lever restoring levers and saddle member are pivoted about a common axis on the frame by front and rear pivot screws. In this type of relay, it is very essential that the lower slotted end of the lever be located, when in its normal position, a predetermined number of degrees off of the vertical with respect to the pivotal axis of the armature while, at the same time, the lower surface of the armature when in its normal operative position shall be parallel to the plane of the top faces of the cores.

An object of this invention is the provision of a fixture for accurately and expeditiously adjusting relay parts.

In accordance with the above object, the invention comprises a fixture which includes a reciprocable pin enterable into the lower slotted end of the relay lever to accurately angularly position such lever in a normal operative position with respect to the pivotal axis of the armature; clamping means operable thereafter to hold the relay with its lever correctly positioned upon the fixture during subsequent locating and adjusting operations. After the relay is clamped to the fixture, a pair of reciprocable forks rotatable to a limited extent and carried by a universally mounted cam lever actuated positioning assembly are moved inwardly over but in spaced relation with the top faces of the cores and then the positioning assembly is rocked downwardly to permit the forks to drop onto the top faces of the cores, where they freely adjust themselves, due to their limited rotary movement and the universal mounting of the assembly, to the plane of the top faces of the cores. In this latter position of the positioning assembly, it will be in parallelism with the top faces of the cores and held therat by its weight. A plate slideable on the positioning assembly and carrying fingers is now moved forward to position rounded forward ends of the fingers under and in engagement with opposite end surfaces of the armature. A fork pivoted

2

on the slide plate and carrying a finger also pivoted on the slide plate intermediate the first fingers is now rocked downwardly to engage the end of the pivotal finger with the top surface of the saddle member to which is fixed the armature and is tightened thereagainst by a thumb screw on the fork bearing against the finger. The armature is now firmly locked parallel to the top faces of the cores while the relay lever is held in its correct angular position and while so positioned, the various stop arms, lugs and armature restoring levers are adjusted to provide the desired action thereof in the operation of the relay.

Other objects and advantages of the invention will be apparent from the following detailed description taken in conjunction with the accompanying drawings, in which

Fig. 1 is a fragmentary plan view of a fixture embodying the features of this invention, the operating parts of the fixture being shown in operated positions with a relay in position on its support and the referred to parts thereof adjusted;

Fig. 2 is a central longitudinal vertical sectional view taken on the line 2—2 of Fig. 1;

Fig. 3 is a vertical view on a reduced scale of a portion of Fig. 2 showing certain parts of the fixture in their inoperative positions, and

Fig. 4 is a vertical sectional view taken on the line 4—4 of Fig. 1.

Referring now to the drawings, particularly to Figs. 1, 2 and 4, there is shown a relay, indicated in general at 10, comprising a base plate 11 of magnetic material having its opposite ends notched at 12—12 (Fig. 4), the notches being used in mounting the relay on the coin collector mechanism with which it is used. The base plate 11 supports a pair of coils 13—17 having magnetic material cores which terminate in pole pieces 21—21 so shaped at their upper ends upon opposed inner faces, indicated at 23—23 (Fig. 4) as to leave but a small air-gap when a pivotal armature 25 is operated to take a position adjacent either of the pole piece faces. The armature structure comprises the armature proper 25 attached by screws 26—26 (Fig. 1) to a saddle or channel-shaped member 27 (Fig. 2) pivoted intermediate its ends by front and rear pivot screws 30 and 31, respectively, on a frame 32 of non-magnetic material, which is frictionally supported on the pole pieces 21—21 and also secured by screws 33 thereto (Fig. 4), the frame surrounding a central magnet 35 fixed to the base plate 11. Also pivoted on the screws 30 and 31 is an armature actuated lever 36 having an offset lower slotted end 37, which in use is connected

to a movable element of an associated coin directing vane (not shown) of the coin controlled apparatus which includes the relay 10.

The lever 36 includes a top portion 38 (Figs. 1 and 2) which extends over the armature assembly in spaced relation, and is slotted at 39 to provide access to the screws 26-26. Upon the front side of the lever 36 (Fig. 2) is an apertured depending lug 42, its aperture being aligned with an aperture in the downwardly extending portion of the lever 36 at the rear of the relay, the two apertures receiving the front and rear pivot screws 30 and 31, respectively, upon which the lever is pivoted. Each end of the lever portion 38 has a central depending lug 43 which is normally slightly spaced from the upper surface of the armature 25 adjacent each end, the lugs serving as stop members for the relay actuated lever to limit its pivotal movement relative to the armature, but at the same time the movement of the armature in either direction about its pivots is transmitted to the lever by the engagement of the armature with the lugs. Also depending from each end of the lever portion 38 at its rear side, is a depending arm 44 which is normally spaced at its lower end a certain distance from the upper surface of the frame 32 and serves as a stop member for the relay actuated lever 36 to limit its pivotal movement in either direction.

Also pivoted on the screws 30 and 31 are two independent armature restoring levers 45-45 extending toward opposite ends of the armature, and each has a central depending arm 46 which normally is spring urged against the upper end face of the adjacent pole piece 21 by coiled tension springs 47-47. Each lever 45 is provided upon its lower surface with circular struck down portions 50 (Fig. 4) engaging the adjacent upper surface of the relay actuated lever portion 38. The function of the spring urged levers 45 is to restore the armature 25 and lever 36, which move as a unit about their pivot pins 30 and 31, except for the limited relative movement theretwixen permitted by the slight spacing of the lever lugs 43-43 from the upper surface of the armature, to their normal positions. In the case of the armature 25, its lower surface should be parallel with the upper faces of the pole pieces 21-21 when in its normal position. With the armature 25 thus normally positioned, the lower slotted end 37 of the lever 36 should be located a predetermined number of degrees off of the vertical with respect to the pivotal axis of the armature.

The adjusting fixture to be presently described serves to accurately position and firmly hold the armature assemblage and the relay lever 36 in their normal positions, as just described, while the depending arms 44-44 of the lever are adjusted by an operator bending them to provide the normal space between them and the upper surface of the frame 32, also the bending of the depending lugs 43-43 on the lever 36 so that they will be normally slightly spaced from the upper surface of the armature, and also the bending of the depending arms 46-46 of the spring pulled armature restoring levers 45-45 so that when the relay is removed from the fixture, after such adjustment, the armature 25 and lever 36 will remain in their normal positions and thus in the operation of the relay they will function properly.

The adjusting fixture comprises a base 51 having a plate 52 fixed to its upper surface which projects from its right end Fig. 2. Fixed upon 75 turned to cause its lower end to engage the U-

the plate 52 at opposite ends in spaced relation are vertical standards 53 and 54. At its upper end the standard 53 is forked and fulcrumed at 57-57 between its furcations is a swivel block 58 which in turn is fulcrumed at 59, upon an axis extending at right angles to the axis of the swivel back 58, to furcations of a forked end of a plate 60. The plate 60 is thus mounted for universal movement within prescribed limits on the standard 53, which permits it to adjust itself to parallelism with the upper end faces of the relay core pieces 21-21 when lowered to its operative position as shown in Figs. 1, 2 and 4. At its opposite end the plate 60 is formed with outwardly and upwardly extending spaced arms 61-61. In the upper portions of the arms 61-61 aligned apertures are provided in which are mounted, for sliding movement in a direction parallel to the axis of the fulcrum 59, slide rods 64-64. Each slide rod 64 is provided at its outer end with a handle 65 and its inner end with a forked formation 66. In addition to its longitudinal sliding movement, each slide rod 64 is capable of a limited rotary movement on its supporting arm 61. Pins 67-67 carried in the arms 61-61 and extending transversely across the slide rods 64-64 and normally slightly spaced from flat surfaces 68 formed on the slide rods intermediate their ends serve to permit the rods and their forked formations 66 to rotatably adjust themselves upon the upper end faces of the relay core pieces 21-21 when the plate 60 is in its operative position (Figs. 1, 2 and 4).

Slidably mounted upon the upper surface of the universally mounted plate 60, by cooperating guide bars 69-69, is a slide plate 70. The movement of the slide plate 70 to the right Fig. 2, is limited by a stop pin 71 fixed to the plate 60 and its movement to its operative position, as shown in Figs. 1, 2 and 4, by an adjustable stop screw 72 (Figs. 2 and 3) also carried by the plate 60. Pivoted at 73 at one end, upon the slide plate 70, is a plate 76 which at its opposite end carries a pair of spaced fingers 77-77 (Figs. 1, 2 and 3), which when the slide plate 70 is moved upon the universally mounted plate 60, when the latter is in its operative position (Figs. 1, 2 and 3), will move under and engage the lower surface of the relay armature 25, the fingers 77-77 being rounded slightly so that they will slide under the relay armature and support the same from underneath in exact parallelism with the top faces of the pole pieces 21-21.

Upon the left end of the pivotal plate 76 (Fig. 2) is pivoted at 79 a forked bracket 80 which is slotted, as indicated at 82 (Fig. 4) at its upper end and the plate 76 normally rests upon a pin 83 fixed in the slide plate 70 and parallel to the plane of the plate 76. Pivoted by one arm 84 thereof, as indicated at 85, to the plate 76 is an inverted irregularly U-shaped member 86 having a stop arm 87 and a depending finger 90. The arm 87 is fitted to slide in the slot 82 of the bracket 80, and the latter has a thumb screw 91 threaded into its outer end which upon the bracket being rocked counter-clockwise, as viewed in Fig. 3, about its pivot 79 to its operative position (Figs. 1, 2 and 4) permits the member 86 to rock, by the action of gravity, in a similar direction to cause the lower end of the finger 90 thereof to enter the slot 39 of the relay lever portion 38 and engage the top surface of the saddle 27 of the relay armature assembly. With the finger 90 in this latter position, the thumb screw 91 is

shaped member 86 within the slot 82 of the bracket 80, the screw being tightened sufficiently to cause the relay armature assembly to be firmly locked in a position which is parallel to the top faces of the relay pole pieces 21—21 between the finger 90 and the fingers 77—77.

In rocking the bracket 80 counter-clockwise the thumbscrew 91, which is released at this time is grasped and the bracket is rocked, until the stop arm 87 on the member 86 abuts the upper end of the bracket, as shown in Fig. 2, the screw then being tightened, as described. In a clockwise movement of the bracket 80 to withdraw the finger 90 from its operative position after releasing the thumbscrew 91, a pin 92 carried by the bracket engages the member 86 which is thus rocked in a similar direction to its inoperative position (Fig. 3).

For clamping the relay 10 to the fixture, the fixture base 51 carries a pair of aligned and spaced plates 93—93 (Fig. 4) from the upper surfaces of which extend relay locating pins 94—94 which are adapted to enter the notches 12—12 in the relay base plate 11. Slidably mounted on the plates 93—93 for longitudinal movement are clamp plates 95—95 which are adapted at their inner ends to be engaged with the upper surfaces of the notched ends of the relay base plate 11. It is to be understood that the relay locating pins 94—94 do not extend quite up to the upper surface of the relay base plate 11. Each of the clamp plates 95—95 is slotted, as indicated at 98 (Fig. 4), at its inner end and is forked at its outer end as indicated at 99. A headed pin 100 extends through the slot 98 and is threaded in the base 51. A compression spring 101 surrounding the pin 100 and bearing at opposite ends against the under surface of the clamp plate 95 and an upper surface of the plate 93, normally urges the clamp plate upwardly above the plane of the upper surface of the relay base plate 11. Pivoted at 102 to each clamp plate 95 at its forked outer end is a lever 105 having a cam formation 106, which bears against the upper surface of the clamp plate when the left hand lever, for example, is rocked clockwise, Fig. 4, thus lowering the inner end thereof into clamping relation with the relay base plate 11. The slot 98 in the clamp plate 95 permits the clamp plate to slide over the relay base plate 11, and to be retracted therefrom, preceding the clamping of the relay 10 on the fixture by the cam levers 105—105 and following the movement of the cam lever to its inoperative position. In their outermost longitudinal positions, the clamp plates 95—95 do not interfere with the mounting of the relay 10 on the fixture.

Fixed to the fixture base 51 between the clamp plates 95—95 and the standard 54, is a vertical plate 107 having a locating notch 108 in its upper portion for receiving and nesting the rear pivot screw 34 for the relay armature 25 as the relay notched base plate 11 is associated with the locating pins 94—94 when the relay is mounted on the fixture. It will be understood that the pins 94—94 serve to locate the relay 10 transversely, and the notch 108 locates it longitudinally on the fixture.

In order to position and hold the relay lever 36 in its normal position during the adjustment of the referred to relay parts, as previously mentioned, there is provided a reciprocable non-rotatable pin 111 which is guided in an aperture in the standard 54. The pin 111 at its right end Fig. 2 is of rectangular shaped cross section, indicated at 112, slightly tapered from its outer end inwardly, and disposed at an angle substantially 75

similar to that of the slot in the offset lower end 31 of the lever. Attached to the left end of the pin 111, Fig. 2, is a forked member 113 to which is pivoted at 114 a hand lever 115 in turn pivoted at 116 to a bracket extending from the sub-plate 52 mounted upon the base 51. Movement of the pin 111 is limited in its movement to its operative position (Fig. 1), wherein its tapered rectangular shaped end 112 is entered in the slot of the relay lever 36 by an adjustable stop screw 119 carried by the forked member 113 on the pin engaging a surface of the standard 54. The movement of the pin 111 to its inoperative position is limited by the lever 115 engaging the standard 53.

In order to lower the universally mounted plate 60 to engage the forked formations 66—66 on the slide rods 64—64 with the upper end faces of the relay core pieces 21—21, as shown in Figs. 1 and 4, and to raise the plate after the relay parts have been adjusted, the following mechanism is provided. Journalled on the standard 54 is a rock shaft 121 (Figs. 1 and 2) to which are fixed spaced cam shaped arms 122—122 which are located in vertical slots 125—125 formed in the upper surface of the standard 54. The cam shaped arms 122—122 are arranged to engage the lower surface of the plate 60 as shown in Fig. 3, upon the shaft 121, being rocked in a clockwise direction by means of a hand lever 126, thus raising the plate. Upon a counter-clockwise movement of the lever 126 to lower the plate 60 the lever will assume a vertical position (Fig. 2). In the lowered position of the plate 60, the cam arms 122—122 are substantially flush with the upper surface of the standard 54, and freely spaced from the lower surface of the plate so that the forked formations 66—66 will rest by gravity on the upper end faces of the relay core pieces 21—21 and the plate 60 will adjust itself in exact parallelism therewith due to its universal mounting.

In using the described fixture it will be assumed that the bracket 80 and the pivotal member 86 having the finger 90 thereon and movable therewith are in their retracted or inoperative positions (Fig. 3) on the supporting plate 76 which carries the fingers 77—77 and is pivoted to the slide plate 70, and that the latter is in its retracted position upon the universally mounted plate 60 and abutting the stop pin 71. Also, that the plate 60 is in its raised position resting upon the cam shaped arms 122—122 with the slide rods 64—64 in their retracted outer positions thereon, the clamp plates 95—95 released and in their outer positions on the plates 93—93 and also that the reciprocatory pin 111 is in its retracted or inoperative position, the fixture is operated in the following manner.

With the various operating parts of the fixture positioned as above described, a relay 10, which is to have parts previously referred to accurately positioned and maintained while other parts are adjusted, is placed upon the fixture with the notched relay base plate 11 associated with the locating pins 94—94 projecting from the fixture plates 93—93 and with the relay rear pivot screw 34 nested in the locating notch 108 of the plate 107. As thus positioned, the relay 10 is transversely and longitudinally located on the fixture.

Thereafter the hand lever 115 is rocked counter-clockwise as viewed in Fig. 1 to move the reciprocatory pin 111 forward to enter its rectangular shaped tapered end 112 in the slot in the lower end 37 of the relay lever 36, as shown in the

drawings, thus insuring that the lever will be accurately positioned and firmly held in its correct angular normal position while other positioning and adjusting operations are completed on the relay 10. After thus positioning the pin 111, the relay clamp plates 95-95 are slid toward each other to position their inner opposed ends over the notched ends of the relay base plate 11. This is effected by grasping and using the hand lever 105-105 to slide the plates 95-95 into position, and thereafter rocking the levers (Fig. 4) in the manner previously described to cause the plates 95-95 to firmly clamp the relay to the fixture as shown in the drawings. Following the clamping of the relay in position, the flat forked formations 66-66 on the slide rods 64-64, the latter being carried on the universally mounted plate 60, are moved toward each other to position them over, but in spaced relation with, the top faces of the relay pole pieces 21-21. The handles 65 are used to thus move the slide rods 64-64, and the inner end faces of the handles abutting the end faces of the slide rod carrying arms 61-61 serve to limit the movement of the formations 66-66 toward each other.

After thus positioning the formations 66-66, the universally mounted plate 60 is lowered by rocking the hand lever 126 in a counterclockwise direction (Fig. 3) to the position shown in Fig. 2. This movement of the hand lever 126 causes the cam shaped arms 122-122, upon which the plate 60 is supported in its upper position to permit the plate to move downwardly, and finally rest in its lowered position by the action of gravity with the slide rod formations 66-66 carried by the plate resting upon the top faces of the relay pole pieces 21-21. Due to the universal mounting of the plate 60 and the limited rotary movement of the formations 66-66, the plate will adjust itself to exact parallelism with the top faces of the relay pole pieces 21-21 in the position shown in the drawings.

The slide plate 10 on the thus lowered plate 60 is now moved to the left to the position shown in Fig. 2, by grasping the bracket 80, the slide plate being moved until it engages the stop screw 72. This movement of the slide plate 10 moves the spaced fingers 77-77 on the plate 10 which is pivoted to the slide plate 10 under and into supporting engagement with the lower surface of the relay armature 25, and thus positioning it in exact parallelism with the top faces of the pole pieces 21-21 as shown in Figs. 1, 2 and 4.

After thus positioning the fingers 77-77, the pivotal bracket 80, which is associated with the pivotal member 86 having the depending finger 90, is rocked counter-clockwise, as viewed in Fig. 2 by grasping the thumbscrew 91, thereby causing the finger to move in a similar direction to its operative position shown in the drawings, the lower end of the finger coming to rest on the top surface of the relay saddle member 27 of the armature assemblage, and thereafter the thumbscrew 91 is tightened. The relay armature 25 is now locked in its normal position parallel to the top faces of the relay pole pieces 21-21 and as previously described, the forked relay lever 36 has been located and locked in its normal position relative to the pivotal axis of the armature.

Thereafter, the lugs 43-43 and arms 44-44 on the relay lever 36, and the arms 46 on the armature restoring levers 45-45 are adjusted by using a suitable bending tool and feeler gauges to provide the desired normal positions thereof relative to the associated relay parts so that the

armature 25 and lever 36 will remain in their normal positions when the relay 10 is removed from the fixture, and the desired action of these parts will result in the operation of the relay.

To remove the thus adjusted relay 10 from the fixture, the operations described hereinbefore in mounting the relay in position on the fixture, positioning and locking the parts in position, are simply reversed.

10 It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A fixture for use in adjusting a pivotal armature of a relay to normal parallelism with respect to end faces of two coil cores associated therewith and for holding the armature in such position during adjustment of various stop members and lugs relative to the armature and core faces comprising, means for locating and supporting the relay in position for such adjustment, a frame, means for mounting said frame for universal movement, a pair of slides movable on spaced portions of said frame to engage said faces of the cores to locate said universally mounted frame in exact parallelism with said core faces, a third slide movable on said frame and carrying fingers adapted to engage one face of the pivotal armature to position the same in parallelism with said pair of slides, a bracket movable upon said third slide, a finger movable upon said third slide and cooperating with said bracket for engaging an opposite face of the armature, and means on said bracket for forcing said finger toward the plane of said first fingers to clamp the armature therebetween and thus force it to exact parallelism with said core faces and hold it thereat while the various relay stop members and lugs are adjusted to the desired positions for retaining the armature in its normal position with respect to said core faces after the relay is removed from the adjusting fixture.

2. A fixture for use in adjusting a pivotal armature of a relay to normal parallelism with respect to end faces of two coil cores associated therewith and for holding the armature in such position during adjustment of various stop members and lugs relative to the armature and core faces and for positioning and holding a pivotal armature actuated lever having a slotted end in a normal position when the relay is positioned on the fixture comprising, means for locating and supporting the relay in position for such adjustment and positioning operations, means operable to enter the slotted end of the relay lever to position and hold it in its normal position, a frame, means for mounting said frame for universal movement, a pair of slides movable on spaced portions of said frame to engage said core faces to locate said universally mounted frame in exact parallelism with said core faces, a third slide movable on said frame and carrying fingers adapted to engage one side face of the pivotal armature to position the same in parallelism with said pair of slides, a bracket movable upon said third slide, a finger movable upon said third slide and cooperating with said bracket for engaging an opposite side face of the armature in an area intermediate said first fingers, and means on said bracket for forcing said finger toward the plane of said first fingers to clamp the armature there-

between and thus force it to exact parallelism with said core faces and hold it thereat while the various relay stop members and lugs are adjusted to the desired positions for retaining the armature in its normal position with respect to said core faces and the operating lever in its normal position after the relay is removed from the adjusting fixture.

3. A fixture for use in adjusting a pivotal armature of a relay to normal parallelism with respect to upper end faces of two vertical coil cores associated therewith and for holding the armature in such position during adjustment of various stop members and lugs relative to the armature and upper end core faces and for positioning and holding a pivotal armature actuated lever having a slotted portion in a normal position when the relay is positioned on the fixture comprising, means for locating and supporting the relay in position for such adjustment and positioning operations, means operable to enter into the slotted portion of the relay lever to position and hold it in its normal position, a frame, means for mounting said frame for universal movement, a pair of slides having a limited rotary movement on spaced arms of said frame to engage said core faces to locate said universally supported frame in exact parallelism with said core faces, a third slide movable on said frame in a direction perpendicular to the movement of said pair of slides and supporting two spaced fingers adapted to engage a lower face of the pivotal armature to position the same in parallelism with said pair of slides, a bracket movable upon said third slide, a finger movable upon said third slide and cooperating with said bracket for engaging an upper face of the armature, and means on said bracket for forcing said finger toward the plane of said two fingers to clamp the armature therebetween and thus force it to exact parallelism with said core faces and hold it thereat while the various relay stop members and lugs are adjusted to the desired positions for retaining the armature in its normal position with respect to said core faces and the relay lever in its normal position after the relay is removed from the adjusting fixture.

4. A fixture for use in adjusting a pivotal armature of a relay to normal parallelism with respect to end faces of two vertical coil cores associated therewith and for holding the armature in such position during adjustment of various stop members and lugs relative to the armature and core faces and for positioning and holding a pivotal armature actuated lever having a slotted portion in a normal position when the relay is positioned on the fixture comprising, means for locating and supporting the relay in position for such adjustment, means operable to enter the slotted portion of the relay lever to position and hold it in its normal position, means for clamping the relay to said supporting means, a plate, means for mounting said plate for universal movement, a pair of slides movable longitudinally on spaced portions of said plate to positions spaced from and above said core faces in a raised position of said plate, means for raising and lowering said universally mounted plate, whereby in its lowered position it will be located in exact parallelism with said core faces when the slides engage said core faces, a third slide movable on said plate intermediate said pair of slides and supporting two spaced fingers adapted to engage one face of the pivotal armature to position the same in parallelism with said pair of slides, a

bracket movable upon said third slide, a finger movable upon said third slide and cooperating with said bracket for engaging an opposite face of the armature, and means on said bracket for forcing said finger toward the plane of said two fingers to clamp the armature therebetween and thus force it to exact parallelism with said core faces and hold it thereat while the various relay stop members and lugs are adjusted to the desired positions for retaining the armature in its normal position with respect to said core faces and the relay lever in its normal position after the relay is removed from the adjusting fixture.

5. A fixture for use in adjusting the armature of a two-core relay with respect to end faces of the cores of an assemblage and to a lever assembly adapted to be actuated by said armature, which comprises a base, a forked plate, means on the base for supporting said plate for universal movement relative to the base, means for positioning said assemblage on the base in a predetermined position with respect to said plate, a pair of means carried slidably on the arms of said plate for engaging said relay armature upon being moved toward each other thereby to position said armature in exact parallelism with said core faces, and means mounted on the base for clamping the armature against said slidable means to hold it in position while portions of the armature-actuable lever assembly are bent to proper relation with the armature.

6. A fixture for use in adjusting the armature and a lever assembly adapted to be actuated by said armature of a two-core relay with respect to end faces of the cores and a relay-mounting portion, respectively, which comprises a base for supporting such a relay thereon, a guideway mounted universally on the base and provided with projections for engaging the end faces of the relay cores, a slide mounted on the guideway, a plurality of clamping jaws carried by the slide for clamping the armature in a predetermined position with respect to the end faces of the relay core, and means mounted on the base for locating the lever assembly in a predetermined position with respect to the relay-mounting portion.

7. A fixture for use in adjusting the armature and a lever assembly adapted to be actuated by said armature of a two-core relay with respect to end faces of the cores and a relay-mounting portion, respectively, which comprises a base, means for engaging the relay-mounting portion to support the relay on the base, a guideway mounted universally on the base and pivotal toward and away from the end faces of the relay, said guideway being provided with projections for engaging the end faces of the relay cores, a slide mounted on the guideway, a plurality of clamping jaws carried by the slide for clamping the armature in a predetermined position with respect to the end faces of the relay cores, and means mounted on the supporting means for locating the lever assembly in a predetermined position with respect to the relay-mounting portion.

ALEXANDER M. MacPHEAT.
